[57] CLAIM

The ornamental design for a shelving unit or the like, substantially as shown.

DESCRIPTION

FIG. 1 is a top perspective view of the shelving unit or the like embodying our ornamental design;

FIG. 2 is a side view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is an enlarged fragmentary sectional view taken in the direction of the arrows on line 7—7 of FIG. 4.
